UNITED STATES PATENT OFFICE.

LEONARD L. FERGUSON, OF CHICAGO, ILLINOIS, ASSIGNOR TO DUNTLEY PNEUMATIC SWEEPER COMPANY, OF CHICAGO, ILLINOIS, A CORPORATION OF DELAWARE.

DESIGN FOR A CASING FOR PNEUMATIC CLEANERS.

45,150.

Specification for Design.

Patented Jan. 13, 1914.

Application filed August 7, 1913. Serial No. 783,618. Term of patent 7 years.

To all whom it may concern:

Be it known that I, LEONARD L. FERGUSON, a citizen of the United States of America, and a resident of Chicago, in the county of Cook and State of Illinois, have invented a new, original, and ornamental Design for a Casing for Pneumatic Cleaners, of which the following is a specification, reference being had to the accompanying drawing, forming part thereof.

The figure is a perspective view of a casing for pneumatic cleaners showing my new design.

I claim:

The ornamental design for a casing for a pneumatic cleaner as shown.

LEONARD L. FERGUSON.
